UNITED STATES PATENT OFFICE.

POVL T. LINDHARD, OF BROOKLYN, NEW YORK, ASSIGNOR TO F. L. SMITH & CO., OF NEW YORK, N. Y., A CORPORATION OF NEW JERSEY.

ROTARY KILN AND COOLER.

Application filed February 12, 1926. Serial No. 87,746.

The invention relates to rotary kilns and coolers of the general type and general construction shown in Letters Patent of the United States No. 1,653,050, dated December 5 20, 1927, and it has for its object to improve the construction of such kilns and coolers in various details to be referred to hereinafter with a view to increased facility in manufacture, to improvement in operation, 10 and to prolongation of use without repair. The invention is particularly concerned with the following features: the closing of the end of the kiln; the support of the cooling drums arranged about the periphery of the kiln and revolving therewith, and the protection of parts particularly liable to wear by the clinker in its movement from the kiln through the cooling drums.

The invention will be more fully explained 20 hereinafter with reference to the accompanying drawings in which it is illustrated and in which:

Figure I is a view in longitudinal sectional elevation of a portion of the kiln with its 25 appurtenances;

Figure II is a view of the same in end elevation as to the right-hand portion and as to the left-hand portion in section on the several planes indicated by the broken lines 30 D—D, E—E and F—F of Figure I.

Figures II^a and II^b are detail views of alternative forms of connection between successive cooling drums of the outer series, the location and direction of the views being indicated by the broken lines A—A and B—B 35 respectively of Figure II.

Figures III and IV are detail views illustrating particularly the connections of the cooling drums of the inner series to the kiln 40 at the forward end of one of such drums, Figure III being a longitudinal section on the plane indicated by the broken line H—H of Figure IV, while Figure IV is a transverse section on the plane indicated by the 45 broken line J—J of Figure III.

Figures V, VI and VII are detail views, respectively in sectional side elevation, in transverse elevation on the plane indicated by the broken line of Figure V, and in top 50 view illustrating particularly the means for supporting the doors by which the end of the kiln is closed.

The kiln may be formed substantially as usual, except as hereinafter indicated, having a shell 1 with a fire-brick lining 5 and

be supported by tires 2 and rollers 3 on foundations 4, one of each of these parts being shown in Figure I. Around the drum, near its lower or discharge end, are supported as hereinafter described, two circumferential series of cooling drums 6 and 7, referred to hereinafter for convenience as drums of the inner series and drums of the outer series. The clinker is discharged from the kiln through lined openings 16 into the 60 drums 6 of the inner series and from each drum of the inner series into the corresponding drum 7 of the outer series, from which the cooled clinker may be discharged through a chute 8 upon a conveyor 9. A 65 hood 10 surrounds the kiln and the cooling drums above at the level of the burner's platform 11 and provides for a proper circulation of cooling air about the cooling drums. The burner's platform is shown as 70 supported upon standards 12 which may conveniently be extended above the platform for the support of the members upon which the fuel pipe and the doors at the end of the kiln are mounted.

The portion of the kiln within the circumferential series of cooling drums is preferably reduced somewhat in diameter externally, as indicated at 15, and near its end are formed the openings 16 through which the clinker is discharged. Each opening is provided with a sleeve lining or bushing 30 which protects the fire-brick lining of the kiln and the frames 13 and 14 external to the kiln and by means of which the corresponding end of each of the inner cooling drums is secured to the kiln, the frames 13 and 14 forming a tubular neck into which the bushing 30 is extended. Each lining or bushing 30 is preferably formed with an external shoulder 31 to bear against the shell 15 and assure the proper positioning of the parts. The linings are further secured in position by cap screws 32 through the frames 13 which are suitably secured to the shell 80 90 95 100 105 110 115 as, for example, by welding. Both the frames 13 and the frames 14 are suitably flanged to receive bolts by which the frames 14 are secured to the frames 13, the cooling drums 6 being supported at their forward ends within the frames 14, as clearly shown in Figures III and IV.

At their rearward ends the inner drums 6 receive flanged frames 17, to which are rigidly secured similar flanged frames 18 110

secured to the rearward ends of the outer cooling drums 7, which are supported at each end from the shell of the kiln by plates 19 and 20 respectively, which are sufficiently flexible to permit the drums 7 to expand and contract longitudinally with the changes of temperature. The plates 19 and 20 are secured to flanged brackets 21 and 22 respectively, secured to the shell of the kiln, and are connected to the drums 7 by flanged brackets 23 and 24 respectively, secured to the ends of the drums 7.

It will be seen that each inner drum 6 is partly supported at its ends by tubular extensions or trunnions 25, secured by bolts 28 to the ends 27 of the drums in registration with central openings therethrough and provided with removable caps 29 to give access to the interior of the drums 6 either for observation or for clearance in case of clogging of the material in the drums. It will be noted that the inner drums 6 will be supported in place by the plates 19 and 20 if the drums 7 are removed for repair or replacement.

It will be understood that when the kiln expands longitudinally toward the discharge end, as indicated by the arrow shown in Figure I, the drums 6 of the inner series, being held rigidly to the kiln at their forward ends, will expand longitudinally in the opposite direction, as indicated by the arrow shown therein and that the drums 7, being rigidly secured to the drums 6 at their rearward ends, will move rearwardly with the longitudinal expansion of the drum 6 and at the same time will themselves expand longitudinally in the opposite direction, as indicated by the arrow shown therein. The movement of the drums 6 and 7 will be permitted by the flexible plates 19 and 20 without danger of rupture of rigid supporting members.

The trunnions 25 are of such size as to be passed easily through the openings 26 formed therefor in the flexible plates 19 and 20 and the bolts 28, by which they are secured to the end plates 27 of the drums, are received in slotted holes in the plates 27 and in the internal flanges of the trunnions, as indicated at 28^a, so as to facilitate the assembling and disassembling of the several members.

The drums 6 are preferably provided with suitable internal flights 6^a so as to facilitate the movement of the clinker therethrough and the drums 7 may be provided with suitable devices, such as chains 7^a and longitudinal ribs 7^b to retard the movement of the clinker therethrough and to promote the interchange of heat between the clinker and the cooling air which moves in a counter-current through the cooling drums.

To prevent the clinker which has passed from the kiln into any of the inner cooling

drums from falling back into the kiln as the drum moves upward in its revolution about the axis of the kiln, there is secured to the inner face of the plate 27 of each drum 6, as by bolts 34, an open frame 33 which carries 70 on that side which is the lower in the upward movement of the drum, a guide or spout 35 which is disposed obliquely with respect to the axis of the drum. As the drum approaches its lowest position, indicated in Figures III and IV, the clinker falls through the lining 30 and between the sides of the frame 33 to the then lowest point of the drum, and as the drum begins to move upward, in the continued revolution about 80 the axis of the kiln, in the direction indicated by the arrow in Figure IV, the clinker drops under or in front of the guide 35 and by it is directed onward into the drum, where its movement is continued by the flights therein, and it is prevented from falling back into the kiln as the drum passes above the plane of the axis of the kiln. A similar guide may be placed in the feeding end of each outer drum 7, as indicated at 85 90 in Figure I.

In order that the drums 7 of the outer series may have proper support circumferentially in the irrevolution about the axis of the kiln, and the stresses upon the flexible 95 plates 19 and 20 may be reduced, and the danger of rupture due to the employment of rigid connections be averted, provision is made for a somewhat flexible or yielding connection between these drums, preferably 100 at each end. Such connections may consist of a plate or strap member bolted at its ends to the supporting frames of two adjacent drums and bowed in a horizontal direction, as shown at 37 in Figures II and II^a, or in 105 a radial direction, as shown at 36 in Figures II and II^b. As the kiln shell 15, to which the inner ends of the flexible plates 19 and 20 are secured, is subjected to higher temperatures than those to which the attaching 110 brackets 23 and 24 are subjected, the plates 19 and 20 would be subjected to severe stresses unless the connections between the drums at the points 23 and 24 were made sufficiently flexible to permit of relative 115 movement between the drums.

To provide for effective closing of the end of the kiln under all conditions, regardless of varying expansion and contraction of the kiln longitudinally, and at the same time to facilitate the manipulation of the closing devices in the operation of the kiln, provisions are made which will now be described, with particular reference to Figures I, II, V, VI and VII.

As shown in Figure I, the kiln shell 15 is formed at its end with an inwardly extending flange 38, to which is secured a channeled annulus 39 which has an outwardly extending flange 40, which may be ma- 130

ched on its inner face for close contact with the outer face of an inwardly extending flange 41 of the two-part door 42. This interlocking of the door with the end of the kiln insures a tight joint under all conditions, the door being supported movably in the direction of the axis of the kiln so that it moves with the end of the kiln in the longitudinal expansions and contractions of the kiln.

To permit the proper assembling of the door and the kiln and to facilitate the opening of the door when necessary, the door 42 is made in two parts which meet in a vertical line in the plane of the axis of the kiln, the two parts being formed with flanges 43 by which they may be secured together. Each part of the door is supported by wheels 44 on a beam 45, extending from side to side, which is itself-supported at its ends by trucks 46 rolling on tracks 47 carried by longitudinally disposed beams 48. As shown in detail in Figures V, VI and VII, each truck is composed of two plates 49 which support a ball bearing 50 to receive the gudgeon 51 secured to the corresponding end of the beam 45, the plates also supporting wheels 52 which run on the track 47. The two-part door is therefore free to conform to all movements of the end of the kiln and thereby maintain a tight joint, while at the same time it may be manipulated easily whenever access to the interior of the kiln is desired. The trucks 47 preferably have the same inclination as the kiln itself so that the flange 41 of the door members is held by gravity in contact with the flange 40 of the kiln.

The door is provided as usual with peep-holes 53, observation doors 54, and an opening 55 for the fuel pipe 55^a. The beam 45, as will be observed, is preferably formed of two channels with a spacer 56 between them at the center to form a stop for the door members. A stop 57 secured to the platform 11 cooperates with brackets 58 on the door members to prevent the door from working out of place in the rotation of the kiln. Upright members 59 support, between its ends, the top member 60 of the frame and furnish convenient support for rollers 61, on which may be rested the bars or pokers which are sometimes required in the removal of clinker rings sometimes formed within the kiln. It may sometimes happen that the draft within the kiln draws the door members forward sufficiently to take the flange 41 of the door members out of contact with the flange 40 of the kiln and thereby permit leakage of air. To prevent this there may be attached to each door member a chain 62 which passes over a pulley 63 attached to upright member 59 and has connected at its other end a weight 64 which is sufficient to hold the door with its flange

41 in contact with the flange 40 of the kiln under all ordinary conditions of pressure.

It will be understood that various changes in details of construction can be made to suit different conditions of use and the convenience of the manufacturer and that, except as pointed out in the claims, the invention is not restricted either to the details of constructions shown and described herein or to the embodiment in one structure of all of the features described.

I claim as my invention:

1. The combination of a rotary kiln for use in the manufacture of cement, having in its end portion a circumferential series of openings through which the clinker is discharged, a circumferential series of cooling drums supported by the kiln about itself and communicating respectively with the kiln through said openings and into which the clinker is directly discharged by gravity, a tubular neck secured to each drum, a removable bushing in each of said openings and extended inwardly beyond the shell of the kiln and externally into said tubular neck to protect the lining of the kiln and the associated parts from wear and means to secure the bushing removably in such position.

2. The combination of a rotary kiln for use in the manufacture of cement, having in its end portion a circumferential series of openings through which the clinker is discharged, a circumferential series of cooling drums supported by the kiln about itself and communicating respectively with the kiln through said openings and into which the clinker is directly discharged by gravity, and a removable bushing in each of said openings and extended inwardly beyond the shell of the kiln to protect the lining of the kiln and the associated parts from wear, the bushing being formed with an external shoulder for contact with the shell of the kiln to position the bushing.

3. The combination of a rotary kiln for use in the manufacture of cement, having in its end portion a circumferential series of openings through which the clinker is discharged, a circumferential series of cooling drums supported by the kiln about itself and communicating respectively with the kiln through said openings and into which the clinker is directly discharged by gravity, a removable bushing in each of said openings and extended inwardly beyond the shell of the kiln to protect the lining of the kiln at said openings and the associated parts from wear, a frame secured externally to the shell of the kiln about each opening, and means carried by the frame and engaging each bushing to hold the latter removably in position.

4. The combination of a rotary kiln for use in the manufacture of cement, having in

- its end portion a circumferential series of openings through which the clinker is discharged, a circumferential series of cooling drums supported by the kiln about itself and 5 communicating respectively with the kiln through said openings, and an obliquely disposed guide within the drum at one side thereof to direct each clinker onward into the drum and to prevent it from falling back 10 into the kiln in the continued revolution of the drum with the kiln.
5. The combination of a rotary kiln for use in the manufacture of cement, having in its end portion a circumferential series of 15 openings through which the clinker is discharged, a circumferential series of cooling drums supported by the kiln about itself and communicating respectively with the kiln through said openings, an end plate for 20 each drum, an open frame secured to the inner face of each end plate, and an obliquely disposed guide supported by the end plate within the drum at one side thereof to direct the clinker onward into the drum and 25 to prevent it from falling back into the kiln in the continued revolution of the drum with the kiln.
6. The combination of a rotary kiln, for use in the manufacture of cement, having in 30 its end portion a circumferential series of openings through which the clinker is discharged, a circumferential series of cooling drums communicating respectively with the kiln through said openings, a plate secured 35 to the kiln at each end of each drum and having an opening therethrough, and a trunnion secured to each drum at each end thereof and entering the opening in the corresponding plate to support the drum.
- 40 7. The combination of a rotary kiln for use in the manufacture of cement, having in its end portion a circumferential series of openings through which the clinker is discharged, a circumferential series of cooling drums communicating respectively with the kiln through said openings, a plate secured 45 to the kiln at each end of each drum and having an opening therethrough, and a trunnion secured to each drum at each end thereof and entering the opening in the corresponding plate to support the drum, the trunnion being hollow and provided with a removable end cap to give access to the interior of the drum.
- 55 8. The combination of a rotary kiln for use in the manufacture of cement, having in its end portion a circumferential series of openings through which the clinker is discharged, a circumferential series of cooling 60 drums communicating respectively with the kiln through said openings, a plate secured to the kiln at each end of each drum and having an opening therethrough, and a trunnion secured to each drum at each end thereof and entering the opening in the corresponding

plate to support the drum, the trunnion being hollow and provided with a removable end cap to give access to the interior of the drum, and the end plate of the drum and flanges of the trunnion being formed with slotted openings for the reception of bolts by which the trunnion is secured to the end plate of the drum. 70

9. The combination of a rotary kiln for use in the manufacture of cement, of a circumferential series of cooling drums supported about the kiln, connections through which the clinker is discharged from the kiln to said drums, a second circumferential series of cooling drums external to the first series 80 of drums and arranged to receive at one end the partially cooled clinker from the drums of the first series and to discharge the cooled clinker at the other end, and flexible plates secured to the kiln and secured to the drums of the external series, one at each end of each drum. 85

10. The combination of a rotary kiln for use in the manufacture of cement, of a circumferential series of cooling drums supported about the kiln, connections through which the clinker is discharged from the kiln to said drums, a second circumferential series of cooling drums external to the first series of drums and arranged to receive at one end the partially cooled clinker from the drums of the first series and to discharge the cooled clinker at the other end, and flexible plates secured to the kiln and secured to the drums of the external series, one at each end of each drum, each drum of the inner series being secured at its feeding end to the kiln and the two corresponding drums of the inner series and the outer series being secured together at 105 the other end. 90

11. The combination of a rotary kiln for use in the manufacture of cement, having in its end portion a circumferential series of openings through which the clinker is discharged, a circumferential series of cooling drums supported by the kiln about itself and communicating respectively with the kiln, and flexible connections between the successive drums. 110 115

12. The combination of a rotary kiln for use in the manufacture of cement, having in its end portion a circumferential series of openings through which the clinker is discharged, a circumferential series of cooling drums communicating respectively with the kiln, flexible plates secured to the kiln and supporting said drums respectively, and flexible connections between successive drums of the series. 120 125

13. The combination of a rotary kiln for use in the manufacture of cement, having at its end an annulus with an outwardly extended flange, a door having an inwardly extended flange to cooperate with the flange 130

of the kiln, tracks inclined away from the kiln, and trucks mounted on said tracks and supporting the removable door.

14. The combination of a rotary kiln for use in the manufacture of cement, having an open end, a two-part removable door to close the kiln, longitudinally disposed tracks at the burning end of the kiln and extending rearwardly thereof, a transverse beam supported on said tracks, and means whereby each door member is independently supported on said beam for movement across the rear end of the kiln in the plane of the beam.

15. The combination of a rotary kiln for use in the manufacture of cement, an annulus at the end of the kiln having a rearwardly and outwardly extended flange to form a circumferential channel at the discharge end of the kiln, a sectional door to close the end of the kiln, an inwardly extending flange on the door projecting into the channel and permitting a limited movement of the door

with respect to the kiln, and means to urge the door rearwardly away from the kiln when the former is in the closed position 25 whereby the flange of the door is maintained in contact with the flange of the annulus.

16. The combination of a rotary kiln, for use in the manufacture of cement, an annulus at the end of the kiln having an outwardly 30 extended flange, a sectional door to close the end of the kiln and having an inwardly extending flange to cooperate with the flange of the annulus, a chain connected to the door, a pulley mounted independently of the kiln structure and over which the chain is guided and a weight connected to the chain tending to move the door away from the kiln to maintain the flange of the door in contact with the flange of the annulus. 35

This specification signed this 11th day of January A. D. 1926. 40

POVL T. LINDHARD.
